SHOE

Filed Dec. 16, 1924

Inventor:
John R. Ayers,
of Emery, Booth, Jamieson & Ayers.

UNITED STATES PATENT OFFICE.

JOHN R. AYERS, OF MALDEN, MASSACHUSETTS.

SHOE.

Application filed December 16, 1924. Serial No. 756,205.

This invention relates to shoes and has for its object to provide a shoe of pleasing appearance and possessing a comfortable and effective support for the arch of the foot.

5 In the accompanying drawings I have shown, merely for illustrative purposes, certain embodiments of my invention wherein:

Fig. 1 is a side elevation of the inner or scaphoidal side of a shoe embodying my invention;

Fig. 2 is a transverse section taken substantially on the line 2—2 of Fig. 1;

Fig. 3 is a plan view of the inner sole of the shoe; and

15 Fig. 4 is a detail side elevation of the shank and instep portions of a shoe illustrating a modified form of the invention.

It will be understood that the present invention is applicable to substantially any kind or type of shoe whether laced or buttoned, high or low; made of leather, canvas, rubber or any other appropriate material. Furthermore it is readily applicable to a Goodyear welt, McKay or any other type of shoe although I have chosen to embody it in a canvas or "sport" shoe so-called and of the Goodyear welt type.

The shoe illustrated in the accompanying drawings comprises an upper 1 composed of two thicknesses 2 and 3 of cloth cemented together, which thicknesses are stitched, as shown most clearly in Fig. 2, between an inner sole 4 and a welt 5 herein by stitches 6 arranged in the usual manner peculiar to a welt shoe. The welt 5 is, in turn, secured by stitches 7 to an outer sole 8 which latter is, in the present example, made up of two layers 9 and 10. The latter layer is desirably composed of "crepe" rubber herein cemented to the layer 9 of relatively stronger material and adapted to support the stitches 7 as well as to maintain the "crepe" rubber section 10 in proper shape.

45 The forward instep edges of both the inner and outer sides of the upper 1 are reinforced by the usual eyelet or fastener strips 11 in which are set appropriate fasteners such, for example, as eyelets 12 through which the usual lacing is arranged.

50 Shoes of the kind illustrated herein or to which the present invention is particularly applicable, are generally heelless or perhaps possess a very low heel and the arches thereof have little, if indeed any, support other than the material of the inner and outer soles. This lack of support causes, in many in-

stances, a falling of the arch including the tarsal and metatarsal bones of the foot.

To resist such a falling of the arch the shoe of the present invention is primarily constructed so that substantially every part thereof contained in a transverse plane intersecting the arch and the instep will snugly fit the foot. Preferably this arch fitting feature of the shoe is effected first, by abnormally cutting away the inner side of the shank of the inner sole 4 approximately to the median longitudinal line of the sole or herein to the line substantially intersecting the center of the heel and the center of the big toe of the 70 foot wearing the shoe as shown most clearly at 13 in Fig. 3. That portion of the last employed in the construction of the shoe that lies adjacent to the cut out part of said inner sole is also materially cut away at 13^a 75 (Fig. 2). This treatment of the inner sole brings the lower edge of the upper where stitched to the welt or sole at its shank well over toward the outside edge of said shank.

When an upper is stretched over a last and an inner sole prepared in accordance with the above, that portion of said upper which covers the region of the scaphoid, internal cuneiform and first metatarsal bones, particularly beneath the arch, will obviously be drawn up 85 farther and more highly arched than will be a normal foot of proper size. Therefore, when such a foot is inserted in the shoe and the same properly laced, that drawn up part of said upper will tend to support the arch 90 of the foot and prevent it from falling. Moreover it will prevent wrinkling of said upper.

To contribute to the supporting effect produced by said upper I desirably provide an 95 arch supporting pad 14 preferably composed of relatively stiff material such as sole leather which is fitted against that portion of the arch adjoining the scaphoid, internal cuneiform and metatarsal bones of the foot. This 100 reinforcing pad may be and preferably is skived or otherwise tapered to lie smoothly against said upper and is secured along its lower margin or edge between said welt 5 and the inner sole 4 by the said stitches 6 105 hereinbefore referred to whereby the upper 3 is secured to the aforesaid members.

The upper edge of the pad 14 is preferably arch-shaped and extends a distance above the welt substantially less than the full height 110 of the shoe upper and this pad is desirably placed exteriorly of said upper so as to pro-

vide a smoother and more comfortable surface for engagement with the foot of the wearer. Obviously the pad 14 may, within the scope and purpose of the invention, be secured in numerous ways in functioning relation to said upper but preferably it is concealed from view behind a reinforcing strip 15 composed of substantially inelastic material such as leather. This strip is designed at least to cover said pad 14 but may, as shown, be extended substantially the length of the shoe from heel to toe along the lower margin of said upper and be secured between the welt 5 and inner sole 4 by the stitches 6 aforesaid.

The upper edge of the strip 15 which preferably lies but a slight distance above said welt is secured by stitches 16 to said upper. If desired this reinforcing strip may be extended entirely around the shoe or, more correctly stated, be carried along both the inside and outside lower marginal portions of the upper. The strip 15 is desirably of substantially uniform width throughout its length except in the region of the pad 14 where it is extended upwardly at 17 to a line at least corresponding with the upper contour of the pad. An additional arch support may be, and herein is, provided by continuing the extension 17 substantially beyond said pad, in fact, to or in the vicinity of the forward edge 18 of the upper 1 terminating preferably at 19 (see Fig. 2). Obviously the stitches 16 whereby the upper edge of the reinforcing strip is secured to the upper 1 may be carried along any appropriate path across said strip or extension but, in the preferred form, I have extended said line of stitches slightly above the upper arched edge 40 of the reinforcing pad 14, as shown at 16^a, leaving the upper end of said strap free with regard to the upper. Desirably in the upper free end of the strap 17 are inserted fastening means similar to those used for lacing or fastening the forward edges of the upper 1 together.

As previously stated the means herein employed for fastening up the shoe include eyelets 12 and, therefore, said strap 17 is provided with eyelets 20 spaced substantially the same as are those in said upper and desirably supplementing the eyelets immediately adjacent part of said upper. In lacing up the shoe, a lacing 21 is inserted in the usual criss cross manner through the eyelets 12 in the strips 11 and, when the extension or strap 17 is reached, said lacing is passed over the edge of the upper which lies adjacent to said strap (see Fig. 2) and through the eyelets 20 of said strap, thence across to the opposite side of the shoe as usual. The result of this method of lacing is to provide a greater tension upon the strap 17 than upon that portion of the upper lying immediately adjacent to said strap causing the upper and

pad 14 to be pressed firmly against the under and inner areas of said arch and thereby providing a substantial and definite support for said arch. The tightening up of the strap 17 naturally tightens everything therebelow as, for instance, the upper 1 and pad 14 so that every part of the circumference of the instep portion of the foot in the plane of said strap will be firmly bound and sagging of the arch prevented. Although the flap or strap 17 has been shown unattached from the upper above the arched row of stitches 16^a it is to be understood that the invention is not limited thereto.

In Fig. 4 I have shown a different arrangement wherein the extension 17^a, substantially similar in form to the extension 17 of Fig. 1, is secured along all sides by stitches 16^b to said upper and eyelets 20^a are inserted through both the extensions 17^a and the shoe upper 1^a. Obviously in lacing up this form the strap 17^a and upper 1^a will be tightened simultaneously against the side of the foot, substantially no relative movement being permitted therebetween.

From the foregoing it will be evident that an efficient, comfortable arch support will be provided in permanent built-in relation to the shoe. The shoe will be neat and pleasing in appearance and extremely comfortable to the wearer by the eliminating of any tendency of the arch to fall and of any rough edges or wrinkles upon the interior thereof.

While I have herein shown and described merely for illustrative purposes, certain specific embodiments of my invention and have disclosed and discussed in detail the construction and arrangement incidental to such disclosures, it is distinctly to be understood that the invention is limited neither to the mere details or relative arrangement of the parts nor to the specific applications herein shown but that extensive variations from the illustrations consistent with the scope of the appended claims may be made without departing from the principles thereof.

Claims:

1. A shoe including an upper, a reinforcing member arranged exteriorly of at least that portion of said upper lying adjacent to the region of the inner tarsal bones of the foot and an arch support interposed between the said reinforcing member and said upper.
2. In a shoe, an upper having a reinforcing member arranged exteriorly of said upper along substantially its entire lower margin and provided with an upwardly extending portion in the region of the scaphoid, internal cuneiform and first metatarsal bones of the foot, and means to apply tension to said upwardly extending portion.
3. In a shoe, an upper, a reinforcing strip extending from heel to toe exteriorly of the lower marginal portion of said upper at least

at the inner side of the foot, a strap extending from the shank portion of said reinforcing strip upwardly substantially to the upper instep edge of said upper and lacing means for applying greater tension to said strap than to the immediately adjacent portion of said upper.

4. In a shoe, a sole, an upper, an arch supporting member secured between said upper and the inner shank portion of said sole, a reinforcing member extending from said

inner shank portion of said sole over said arch supporting member and substantially to the instep edge of said upper, and means to apply tension to said reinforcing member for the purpose of maintaining said upper and said arch supporting member in constant supporting relation to the arch of the foot of the wearer.

In testimony whereof, I have signed my name to this specification.

JOHN R. AYERS.
